UNITED STATES PATENT OFFICE.

FOREST E. CULVER, OF CHICAGO, ILLINOIS.

PLIERS.

1,061,358.

Specification of Letters Patent. Patented May 13, 1913.

Application filed July 5, 1912. Serial No. 707,816.

To all whom it may concern:

Be it known that I, FOREST E. CULVER, a citizen of the United States, residing at Chicago, in the county of Cook and State 5 of Illinois, have invented new and useful Pliers, of which the following is a specification.

The present invention relates to improvement in pliers, the primary object of the 10 invention being the provision of a novel form of ratchet locking and releasing device disposed between and carried by the respective gripping handles of the pliers, the movable member being held resiliently in ratchet 15 engaging position and capable of a longitudinal swinging movement, whereby no strain is placed upon the gripping jaws of the pliers that would tend to twist or break the object held in the jaws, either during the 20 locking or releasing of the pliers.

With the foregoing and other objects in view which will appear as the description proceeds, the invention resides in the combination and arrangement of parts and in 25 the details of construction hereinafter described and claimed, it being understood that changes in the precise embodiment of the invention herein disclosed may be made within in the scope of what is claimed without de- 30 parting from the spirit of the invention.

In the drawings Figure 1 is a side elevation of the needle holding pliers constructed according to and embodying the present invention, the handles being in locked position: 35 Fig. 2 is a longitudinal sectional view through the handles of the pliers showing the present invention applied. Fig. 3 is an enlarged detail view of the handle adjacent to the portion carrying the pivoted member 40 of the ratchet locking device. Fig. 4 is a perspective view of such pivoted member. Fig. 5 is a perspective view of the spring for controlling the pivoted member. Fig. 6 is a detail view of the free end of the main 45 handle separating spring.

Referring to the drawings, the numerals 1 and 2 designate the gripping handles of the pliers which are pivoted as usual at 3, and are provided with the object gripping jaws 50 4 and 4' respectively.

The handle 2 is provided with the two integral and spaced lugs 5 having disposed therebetween the pin 6 having the straight wall 6', as clearly shown in Fig. 2. The 55 pivoted member 7 of the ratchet locking device is provided with a slot 8 having the

seat 8' for the reception of the curved portion of the pin 6, the throat 8" leading therefrom to permit of the ready introduction of the pivoted member 7 between the 60 lugs 5 to be seated upon and pivoted by the pin 6. The pivoting end of the member 7 is flattened as at 9, while the outer end is provided with the hooked terminal 10 and with the offset curved guiding portion 10' 65 upon one side thereof. A flat spring 11 is disposed between the lugs 5, the pin 12 securing one end thereof to the handle 2, while the free end is disposed for sliding movement to engage the handle 2 at 13, the 70 intermediate portion of the spring 11 being placed in engagement with the flattened portion 9 of the pivoted locking member 7, so as to provide a resilient cushion for the pivoted member 7 and to permit the same to 75 have its free end moved longitudinally of the handle 12, and to normally be held in one position. The stationary locking member 14 is threaded at 15 to the handle 1 and is provided with the elliptical pointed end 16 80 which is disposed in the path to permit of the ratchet teeth 17 to engage or co-act with the hook 10 of the free end of the pivoted member 7, the curved portion 18 acting as a guide to guide the free end 10 downwardly, 85 with the movement of the handle 2 toward the handle 1, while the curved portion 19 acts as a guiding means to engage the offset portion 10' of the member 7 when the hook 10 has been moved beyond the last tooth 17 90 above and over the upper curved portion 19 of the free end of the stationary member 14.

In the movement of the hooked end 10 in engagement with the respective teeth 17, the action of the teeth thereupon will cause the 95 end 10 to be depressed longitudinally of the pliers so that when the hooked end 10 is moved beyond the last tooth 17, the tension of the spring 11 will be such as to move the offset portion 10' upwardly and thus permit 100 the same to ride upon the upper curved portion 19 of the stationary member 14.

In order to normally have the handles 1 and 2 separated, a flat spring 20 is connected at 21 to the handle 1, the free end 105 being slotted as at 22 with the terminals 23 forming a support for the sleeve 24 roller 24, the hook 26 carried by the handle 2 being disposed within the slot 22 and co-acting with the roller 24 to limit the full extent 110 of the handles 1 and 2.

From the foregoing description, taken in

connection with the drawings it is evident that with a ratchet locking device as herein set forth, that the depression of the handles toward each other will cause the pivoted member 7 to be placed in engagement with one of the teeth 17, thus locking the jaws 4—4' in needle gripping position, and that to release the gripping ends, the handles will be further pushed toward each other until the offset portion 10' is beyond the last tooth, at which time the spring 11 exerting a tension upon the free end of the member 7 will move the same so that the offset 10' will ride upon the curved portion 19. The handles now being under the tension of the spring 20 will be automatically separated. By mounting the pivoted member 7 for longitudinal swinging movement instead of horizontal swinging movement, no torsion is thrown upon the gripping ends 4 and 4' and the liability to break the gripped object held between the jaws is lessened.

What is claimed is:

25 1. Pliers, having two spring extended handles, a stationary stud carried by one handle intermediate of its ends, the free end of said stud being provided with an offset projection having a plurality of ratchet teeth upon one side and a curved portion upon the opposite side, two spaced lugs carried by the other handle, a pin having a flattened outer face mounted in the two lugs, a trigger having a slotted head upon its inner end for disposition between the lugs, the slot fitting upon the pin and forming a pivot for the trigger, said trigger having a hook with an offset portion upon its outer

free end, and a flat spring between the spaced lugs and bearing against the adjacent portion of the head of the trigger to resiliently hold the free end of the trigger for registration with the free end of the stud when the handles are depressed, the depression of the handles and the meeting of the free ends of the arm and stud, causing the hook of the trigger to be moved against the spring and into engagement with the ratchet teeth, a further depression of the handles causes the hook of the trigger to be moved beyond and free of the ratchet teeth while the spring of the handle separates the handles and the trigger spring causing the offset hook of the trigger to rise and ride upon the curved portion of the offset of the stud.

2. A pliers having two handles, means carried by the handles for locking the same when moved toward each other and to be released upon the final movement of the handles toward each other, a flat spring having one end fast to one of the handles with its free end slotted, an anti-frictional roller mounted in the free end for engagement with the other handle, and a hooked stud carried by the last handle and projected through the slotted end of the spring to contact with the anti-frictional roller to limit the extension of the handles.

In testimony that I claim the foregoing as my own, I have hereto affixed my signature in the presence of two witnesses.

FOREST E. CULVER.
